DESIGN FOR A BROOCH PIN OR SIMILAR ARTICLE

Albert Horwig, New York, N. Y.

Application February 15, 1940, Serial No. 90,285

Term of patent 3½ years

To all whom it may concern:

Be it known that I, Albert Horwig, a citizen of the United States of America, residing in New York city, in the Borough of Manhattan, county and State of New York, have invented a new, original, and ornamental Design for a Brooch Pin or Similar Article, of which the following is a specification, reference being had to the accompanying drawing, forming part thereof, wherein,

I claim:

The ornamental design for a brooch pin or similar article, substantially as shown.

ALBERT HORWIG.
